ENVELOPE STUFFING MACHINE

Russell H. Thompson, Indianapolis, Ind.

Application October 21, 1943, Serial No. 507,101

17 Claims. (Cl. 93—6)

This invention relates to a stuffing machine for inserting folded letters, folded inserts or circulars or both into an open envelope.

It is to be observed that printing machines are available which will print and fold reading matter as desired. Also, machines are available to address envelopes from address plates, etc. Also, machines are available to seal envelopes, or seal and stamp same, or seal and meter mail stamp same.

All of these last mentioned machines are well known in the circularizing, etc., art and offers no problem to the expeditious and repetitious operation inherent in each machine. The only intermediate problem has been the insertion of the folded letter, or advertising, or both, mechanically and expeditiously into the envelope.

Herein envelopes are utilized with the flap open and not folded.

The chief object of the present invention is to simplify stuffing machines of the general character specified.

The chief feature of the present invention resides in the inline arrangement of reservoirs for the aforesaid envelopes and letters and/or inserts and the reciprocatory stuffing ram, whereby a machine not much over fifteen to eighteen inches wide and about two to two and a half feet long can expeditiously handle, and automatically stuff thousands of envelopes in an hour.

Of course, if more inserts are to be included in the envelope, the machine would be proportionately elongated and instead of having two or three reservoirs, as herein disclosed, same would include four or more, all, however, being tandem or in-line arranged and all associated with a single reciprocatory pusher or ram.

Other objects and features of the invention will be set forth more fully hereinafter.

The full nature of the invention will be understood from the accompanying drawings and the following description and claims:

In the drawings, Fig. 1 is a top plan view of one and the preferred embodiment of the machine, there being three reservoirs included therein and these of adjustable area, the height thereof being about fifteen inches more or less, same having been found most convenient and of considerable storage capacity.

Fig. 2 is a longitudinal sectional view.

Fig. 3 is a horizontal view taken in the plane indicated by broken line 3—3 of Fig. 2 and in the direction of the arrows.

Fig. 4 is a transverse sectional view taken on

broken line 4—4 of Fig. 1 and in the direction of the arrows and of the open envelope reservoir.

Fig. 5 is a view similar to Fig. 2 and of a modified form of finger and operating mechanism therefor.

Fig. 6 is a view similar to Fig. 2 and of a modified form of finger and operating mechanism therefor.

In the drawings, 10 indicates a base plate suitably supported by legs or the like 11 connected as at 12. Plate 10 herein is divided to form coextensive slot 13. A pair of angles 14, spaced a lesser distance apart than the slot 13, is wide, forms a seat for member 15 to which is secured at 16 depending member 17, see Fig. 4. This member 17 is of stirrup type (see Fig. 2), although it might well be a singularly slotted member, providing slot 18 therein.

Member 15 has secured to its upper right hand end, as at 19, the pusher or ram member 20, see Figs. 1 and 2. Note that the forward edge 21 thereof is spaced appreciably forward from member 22, see Fig. 2, and this distance preferably is approximately that of or in excess of the deepest envelope for reasons hereinafter stated.

An upright, transversely extending, plate 23 is suitably secured to base 10, as by ears 24 and screws 25. This plate includes forwardly directed ledge 26 near the base 10. Adjacent each end of plate 23 and extending at right angles to plate 23 are the smaller plates 27 having oppositely directed flanges 28 at their lower ends.

A pair of aligned, elongated, spaced slots 29 in plate 10 and parallel to plate 23 seat threaded anchor members 30 carrying wing nuts 31 by which the plates 27 can be adjusted transversely upon the base 10 and at the desired distance apart. Note that said slots are so spaced from plate 23 that members 27 can, without interference from shelf or ledge 26, be brought closer together and to the limit substantially determined by the spacing between aligned slots 29.

In the base 10 and at each side of the path of ram 20 and extending rearwardly from approximately the forward edge of ledge 26 are the elongated parallel slots 32 in each of which is mounted finger 33 to which reference will be had more fully hereinafter.

Forwardly of plates 27 and in base 10 are the elongated parallel slots 34 and a U-shaped plate or channel member 35 with oppositely directed ears 36, which receives threaded member 37 seated in said slots 34 and by means of wing nut 38 member 35 may be secured to base 10 and parallel plate 23 and at the desired distance for-

wardly thereof. Secured to the base 10 adjacent plate 35 and at opposite sides of the path of ram 20 are the support plates or blocks 39 tapered or relieved as at 40.

The lower edge of plate 35 terminates sufficiently above the upper plane of members 39 so as to pass a unit (circular letter, etc.), therebeneath as hereinafter described. To insure passage of but one unit, see Fig. 4 for details, plate 35 at each side of the ram path slidably mounts vertically reciprocable member 41 with rubber tip 42 and normally constrained to lower position determined by the top plane of members 3. These members are aligned or register with fingers 33, as shown in Fig. 1.

The foregoing, plate 23, side plates 21 and forward plate 35, constitute a reservoir obviously adjustable to size of insert unit (folded letter or circular). This unit is designated by letter A in Fig. 2. It will be noted such unit includes two folds *a* and *a'* and an upper wider portion *a*². The weight of a stack of such units, gravity or a weight follower on the top of the stack causes portions *a* and *a'* to press downward upon members 39 and the rearward edge of portion *a*² is held elevated by ledge 26, so that fingers 33 can move forward between portions *a*² and *a* when said fingers move forward followed by the ram 20 therebetween, see Figs. 1 and 4.

Forwardly of the aforementioned reservoir is a duplicate thereof. In the same is stack of folded letters B with portions *b* and *b'* of smaller folds than portion *b*² which rests upon ledge 26. When insert A is ram engaged and passed below the lower edge of plate 35, same passes between portions *b*² and *b* now separated by the second set of fingers 33 until the ram carried insert A is nested in insert or letter B and carried forwardly with the ram below the lower edge of the second plate 35. Fig. 2, second reservoir, shows units A and B nested for transfer.

Forwardly of these two reservoirs is the envelope reservoir. Rigid with plate 10 are the spacer blocks 50 carrying the cross bar 51 (ledge 26 equivalent) slotted as at 52 for finger 33 passage or clearance. This cross bar has a forwardly directed support portion 53. At each side is a curved plate 54 carried by flange 55 adjusted by member 56 seated in transverse slot 57 and tightened by wing nut 58.

Forwardly of the aforesaid are the spaced blocks 59 sloped as at 59a and over which is mounted a U-shaped plate 60, similar to plate 35, and longitudinally adjusted by parallel, elongated, longitudinally directed slots 61 in plate 10 and by members 62 and wing nuts 63 which clamp flanges 64 on plate 60. Same also mounts members 41 with tips 42 as aforesaid. The details of such member 41 mounting is shown clearly in Fig. 4.

In the resulting reservoir is a stack of open flap envelopes C having the back *c*', the front *c* and flap *c*². In Fig. 2 insert A and B are illustrated as nested in envelope C. Observe that in Fig. 2 all parts are in the initial or starting position, and the units A, B and C in nested relation is illustrative of nesting and stuffing, not of actual conditions at any one time or instant.

The envelope, address side up with flap resting on portion 53 is opened by fingers 33 movable in slots 32 and 52, so that the stuffing ram can follow through with nested insert and folded letter and stuff the envelope. Continued travel of the ram to the right forces the stuffed envelope below the lower edge of plate 60 and beyond same.

The stuffed envelope, as it passes forwardly, has its lower edge engage depending portion 65 of an angle member pivoted at 66 and having its free end 67 connected by spring 68 to anchor 69.

5 These angle members are tilted upwardly and outwardly distending springs 68. When the ram reverses its travel direction, these members hold the envelope and its contents against rearward travel and insure positive separation. The stuffed envelope then falls downwardly to a receiver not shown, or to a conveyor of a sealing machine as before described.

When the combined units are of sufficient weight, same automatically strip from the ram upon its retrograde movement. It will be remembered that the length of the ram was important. It now appears it must be long enough to pass beneath plate 60 an amount sufficient to push the entire unfolded or open flap envelope 20 beyond plate 60 and its rubber fingers 42.

In each instance rubber fingers 42 serve as yielding retainers, permitting escape from each reservoir of only one unit from that reservoir at a time.

25 Reference will now be had to the means for moving the several sets of fingers and the ram. It will be recalled, see Fig. 4, that depending from plate 10 are channels 14. Pivoted therein at 70, below each slot or aperture 32, is an ear 30 71 carrying arm 72 with another ear 73. The upper end of arm 72 is curved upwardly and forwardly as the finger 33.

A longitudinally directed bar 74 connects at 75 to all ears 73 of one longitudinal series of 35 fingers. The rearward end of each of the pair of bars 74 at 76 is connected to a link 77 in turn connected to a crosshead 78 at 79. A pair of springs 80 is connected at 81 to the crosshead and at 82 to the underface of base 10.

30 The crosshead 78 may be provided with arm 83 adapted to engage stop 84 carried by stem 85 of piston 86 in cylinder 87 containing spring 88 and serving as a cushioning dashpot. The cylinder is secured to base 10 as at 89.

45 When the ram is retracted beyond the first reservoir, it picks up the crosshead 78 and moves it to the left in opposition to springs 80, thus loading or tensioning same. The crosshead may engage cushion stop 90, see Fig. 2.

50 When the ram moves forward, springs 80 cause crosshead 78 to travel similarly, which throws all fingers upwardly and forwardly and simultaneously, this movement, as stated, being dashpot cushioned, if desired, as illustrated. The 55 ram-crosshead contact is by member 91 and the stirrup 17. Forward movement of fingers 33 may be limited by any arm 72 engaging the forward end of its slot 32, or other suitable means.

The means for reciprocating the ram includes 60 the crosshead 15, stirrup 17 and a roller 92 carried by a shaft 93 secured to and projecting laterally of endless belt 94 passing about fore and aft spaced drums 95 and 96 mounted on shafts 97 and 98, respectively, carried by depending 65 bearings 99 and 100, respectively. These may be adjusted for belt tensioning, see Fig. 3. Shaft 98 is elongated and carries pulley 101 by which same may be driven by a belt and motor-reducer drive, or any other suitable source of rotational power, not shown.

As pulley 101 is rotated, drum 96 is rotated, hence belt 94 is caused to travel and always in the same direction. Since roller 92 is carried therewith, stirrup 17 perforce follows, roller 92 75 raising and lowering in slot 18, as required, as the

roller raises to the upper level at the start of cycle and then lowers at the half cycle and raises at the end of the cycle. Hence, ram 20 is caused to reciprocate with but slight dwell periods at the travel limits incident to travel direction reversal.

As long as pulley 101 is rotated and the reservoirs are kept filled, the stuffer will be automatic and repetitious in operation. Note that the fingers are projected upwardly and forwardly at all times until the ram approaches its rearward limit of travel, whereupon the fingers are lowered and retracted. When so positioned (the ram is now fully retracted) all lowest members in the several reservoirs lower until the uppermost rearward portion thereof rests above the lowermost forward portion. Upon ram initial travel forwardly, the fingers advance and elevate for separating purposes as described. No further description of operation is believed necessary.

In Fig. 5 a modified form of finger structure is illustrated. In this form the link rod or actuator 174 similar to rod 14, Fig. 2, is pivotally connected to successive fingers 172 at 175. Herein pin 170 carried by the lower end of arm 172 rides in an elongated slot 171 in frame 114. Rod 174 is slidably guided by brackets 173. Each arm has finger extension 133 associated with slot 132 as before described.

Herein, since arm-finger 172-133 moves fore and aft with rod 174 and raises and lowers finger 133 permitted by slot 171, the desired action can be obtained. This action in many cases is more desirable than that actually obtainable wherein the fingers have arcuate travel only about pivots 70.

In Fig. 6 a modified form of finger operating mechanism is illustrated. In said figure the folded letter or insert shows the short fold closely adhering to the adjacent portion due to previous pressure static attraction, etc. The present finger 233 has a retracted position so that its entering end is immediately adjacent ledge 226.

Initial finger movement causes separation of the folded letter or insert and continued finger movement elevates the stack thereof to free the mutually adhering portions. The dotted arc above slot 232 indicates this travel. This form includes the vertical pin and slot connection 271, an eccentric 273a pivoted on the frame at 273 and pivotally connected to arm 272 at 275. Herein guides for rod 275 are omitted and a link 276 connects rod 275 to member 277 actuatable like members 17 and 177.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. Mechanism for stuffing envelopes and/or nesting inserts comprising in combination a plurality of substantially open mouthed reservoirs sequentially arranged and having their mouths substantially coplanar, and a single ram movable adjacent the mouths and from reservoir to reservoir in succession for the purpose described, each reservoir including at its rearward side a unit supporting ledge means immediately above the ram path of movement, the reservoir mouth permitting positioning of the ledge means sup-

ported unit in the path of the ram, the reservoir having a unit discharge lateral outlet opposite the said ledge means.

2. Mechanism for stuffing envelopes and/or nesting inserts comprising in combination a plurality of substantially open mouthed reservoirs sequentially arranged and having their mouths substantially coplanar, a single ram movable adjacent the mouths and from reservoir to reservoir in succession for the purpose described, each reservoir including at its rearward side a unit supporting ledge means immediately above the ram path of movement, the reservoir mouth permitting positioning of the ledge means supported unit in the path of the ram, the reservoir having a unit discharge lateral outlet opposite the said ledge means, and finger means for each reservoir and juxtaposed to the mouth of the same and movable into the reservoir mouth in timed relation to ram movement.

3. Mechanism for stuffing envelopes and/or nesting inserts comprising in combination a plurality of substantially open mouthed reservoirs sequentially arranged and having their mouths substantially coplanar, a single ram movable adjacent the mouths and from reservoir to reservoir in succession for the purpose described, each reservoir including at its rearward side a unit supporting ledge means immediately above the ram path of movement, the reservoir mouth permitting positioning of the ledge means supported unit in the path of the ram, the reservoir having a unit discharge lateral outlet opposite the said ledge means, and continuously movable means for moving the ram, said continuously movable means effecting reciprocation of said ram.

4. Mechanism for stuffing envelopes and/or nesting inserts comprising in combination a plurality of substantially open mouthed reservoirs sequentially arranged and having their mouths substantially coplanar, a single ram movable adjacent the mouths and from reservoir to reservoir in succession for the purpose described, each reservoir including at its rearward side a unit supporting ledge means immediately above the ram path of movement, the reservoir mouth permitting positioning of the ledge means supported unit in the path of the ram, the reservoir having a unit discharge lateral outlet opposite the said ledge means, and continuously movable means for moving the ram, said continuously movable means effecting reciprocation of said ram, and comprising an endless structure and a pin and elongated slot connection between the endless structure and the ram.

5. A method of stuffing envelopes including facing downwardly an open flap envelope with its front up, positively separating the front and back of the envelope at the mouth thereof and then stuffing the envelope while the mouth is held open, there being relative movement between the envelope and stuffing material, the stuffing material being folded and the folded material being slightly opened to nest initially other material by relative movement therebetween, the nested and folded material subsequently being stuffed into the envelope.

6. A method of stuffing envelopes including facing downwardly an open flap envelope with its front up, positively separating the front and back of the envelope at the mouth thereof and then stuffing the envelope while the mouth is held open, there being relative movement between the envelope and stuffing material, the stuffing material being folded and the folded material being

slightly opened to nest initially other material by relative movement therebetween, the nested and folded material subsequently being stuffed into the envelope, the other material also being folded, the nesting and stuffing being effected by successively advancing the material toward the envelope.

7. A method of stuffing envelopes including facing downwardly an open flap envelope with its front up, positively separating the front and back of the envelope at the mouth thereof and then stuffing the envelope while the mouth is held open, there being relative movement between the envelope and stuffing material, the stuffing material being folded and the folded material being slightly opened to nest initially other material by relative movement therebetween, the nested and folded material subsequently being stuffed into the envelope, the folded material being held open for other material reception therein and until it is fully nested therein.

8. Mechanism for stuffing and infolding purposes comprising in combination a plurality of longitudinally aligned open mouthed reservoirs, each for unit reception and having a ledge positioned opposite a lateral outlet and spaced slightly from the mouth, a pair of spaced fingers for each reservoir and movable into the mouth and towards the outlet, and a ram movable beneath each ledge and outlet in succession and between said pairs of fingers.

9. Mechanism, as defined by claim 8, wherein all fingers are simultaneously movable into the reservoir mouths and simultaneously retracted therefrom.

10. Mechanism, as defined by claim 8, wherein the ram has a reciprocatory cycle of travel.

11. Mechanism, as defined by claim 8, wherein all fingers are simultaneously movable into the reservoir mouths and simultaneously retracted therefrom, the ram having a reciprocatory cycle, the fingers normally being constrained in one di-

rection and movable oppositely incident to a portion of the cyclic ram movement.

12. Mechanism, as defined by claim 8, wherein all fingers are simultaneously movable into the reservoir mouths and simultaneously retracted therefrom, the ram having a reciprocatory cycle, the fingers normally being constrained in one direction and movable oppositely incident to a portion of the cyclic ram movement, and dash pot cushion means for cushioning the constraint movement of fingers.

13. Mechanism, as defined by claim 8, wherein each reservoir adjacent its outlet includes means normally constrained to prevent multiple unit discharge from that reservoir, said ram having a linearly reciprocatory cycle of travel.

14. Mechanism for stuffing and infolding purposes comprising in combination a plurality of longitudinally aligned open mouthed reservoirs, each for unit reception, the reservoir mouths lying in spaced relation to a support, finger means juxtaposed to the support and movable into each mouth and across the same, a ram for moving said finger means.

15. Mechanism as defined by claim 14 wherein each finger means is pivoted below the reservoir mouth and the moving means includes an interconnection between the finger means.

16. Mechanism, as defined by claim 14, wherein each finger means includes a pin and slot connection below the reservoir mouth and the moving means include a singular member to which each finger means is pivotally connected.

17. Mechanism, as defined by claim 14, wherein each finger means includes a pin and slot connection below the reservoir mouth and the moving means includes a singular member to which each finger means is pivotally connected, and a pivotally mounted member having eccentric type connection with said singular member and said finger means.

RUSSELL H. THOMPSON.
